UNITED STATES PATENT OFFICE.

EVERETT A. MARLOWE, OF PRESCOTT, ARIZONA.

COMBINED TRUNK AND BED.

Specification of Letters Patent.

Patented May 25, 1915.

1,140,991.

Application filed December 10, 1914. Serial No. 876,566.

To all whom it may concern:

Be it known that I, EVERETT A. MARLOWE, a citizen of the United States, residing at Prescott, in the county of Yavapai and State 5 of Arizona, have invented certain new and useful Improvements in Combined Trunks and Beds, of which the following is a specification.

The present invention appertains to that 10 class of collapsible structures designed particularly for the purpose of forming a combined trunk and bed, the object in view being to provide coöperating receptacle forming members which when extended may constitute a bed, the essence of the invention 15 lying in the provision of connecting means for the complementary receptacle members which permits of their extension as well as their pivotal movement relative to one another.

A further object in view is to provide means for coöperating with the pivotal connection aforesaid such that the pivot is rendered rigid when the sections are in extended position.

Another object contemplated is the employment of brace means for the bed supporting elements which perform a dual function in that they constitute locking 30 means to hold the sections in extended position, incidentally coöperating for this purpose with the pivot stiffening means which are also held from displacement by the brace members.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a perspective view of a device forming the embodiment of my invention 45 shown in extended position constituting a bed. Fig. 2 is an end elevation showing the complementary sections of the device in the position assumed upon initial opening movement prior to extension. Fig. 3 is an end 50 elevation of the invention in folded or closed position. Fig. 4 is a longitudinal sectional view through the device parts being broken away and shown in section. Fig. 5 is a transverse sectional view through the device 55 in closed position. Fig. 6 is an enlarged frag-

mentary sectional view showing more clearly a sliding connection intermediate the coöperating sections. Fig. 7 is a plan view of the detail shown in Fig. 6, parts being broken away and shown in section. Fig. 8 is a 60 transverse sectional view on the line 8—8 of Fig. 7. Figs. 9, 10, 11, 12 and 13 are sectional views taken on the planes indicated by the lines 9—9; 10—10; 11—11; 12—12 and 13—13 respectively of Fig. 4. 65

Throughout the following detail description, and on the several figures of the drawings, similar parts are referred to by like reference characters.

Referring to the drawings and specifically 70 describing my invention, it will be observed that the device in essential characteristics comprises two coöperating sections 1, 2, which are complementary to each other and when in coacting relation form a rectangular 75 container somewhat of the configuration of a trunk. The sections are formed by dividing the rectangular construction diagonally from an upper corner to a lower corner, as best noted by reference to Fig. 3. Thus 80 each section is what may be termed triangular in cross section, and this form is especially advantageous in producing a device susceptible of being collapsed into compact 85 form but yet permitting of extension which will provide a good sized couch or bed. It will be observed by reference to Fig. 1 that a side or wall of each section is hingedly connected to the main body portion of the section as designated by the numerals 3 and 90 4, these sides or walls constituting supports for the device when extended and when disposed in elevated position with respect to the ground or surface on which it rests. These side walls 3 and 4 have pivotally connected thereto suitable braces 5 and 6 and in addition to the bracing function which holds the sides in vertical position, the braces of one side have an interlocking connection to be more clearly described hereinafter. The several figures of the drawings 95 clearly depict the use of angle irons in the make-up of each of the complementary sections 1 and 2 and to enable extension of these sections or separating movement one 100 from the other, section 2 is provided at each side with a slide 7 hingedly connected at 8 to the angle iron at its corresponding side, the extremity of each side having a notch 9 which is adapted to interlock with a lug 10 110

- formed on the section 1 so as to limit the extension of the sections. As will be observed by reference to Fig. 4 and the sectional Figs. 9, 10, 11 and 12, the angle iron 5 of the section 1 is formed with an overhanging guide flange 11, at each side which coacts with the angle extension slides 7 to properly guide these members in their extension movement.
- 10 In the receptacle form the closed condition of the device, the slide members 7 lie adjacent and within the sides, or more properly speaking the end members of section 1 and the hinge connection 8 thus afford a pivotal movement to the section 2 to enable said section to be moved into position corresponding to section 1 as disclosed in Fig. 2, preliminary to the separating of said sections for forming the bed. To render the 15 pivotal movement inoperative when the sections are separated in the bed form, I provide at each side of section 2, coacting with its horizontal angle iron members, a slide bar of angle iron construction designated 20 12, each of these bars has an open end slot 12' at one extremity and a longitudinally extending slot 12'' extending the greater portion of its length. Projecting into the slot 12' are lugs 13 which secure the slide 25 to the angle iron of section 2 and furthermore the angle iron of this section is formed with an overhanging guide flange 14 holding said slide in proper relation. To make the pivot or hinge connection 8 rigid, as 30 before mentioned, the slides 12 are moved from the dotted line retracted position shown in Fig. 6 to the full line position where said slides extend over said hinge connection and the extremity of each indicates that a lug 15 carried by the extension 35 slide 7 at the corresponding sides with which lug the side slot 12' of the slide is engaged. This holds the form in extended horizontal position and as shown in Fig. 1 a flexible 40 spring support of any desired character, 16, which is connected at its opposite ends to the respective sections 1 and 2 is stretched for holding the bed clothing or mattresses that may be used in conjunction with the device.
- 45 Each of the slide bars 12 is provided with a pair of openings 17, 18 each of which openings is adapted to register with the corresponding opening 19 in the angle iron of the section 2, when the slide bars are in the initial inoperative position shown in dotted lines of Fig. 6 and the full line position of said figure, respectively. When the slide bar 12 is in the former position, the brace 6 at the corresponding side of section 2 extends upwardly 50 into the said section, as clearly shown in Fig. 5, and in the opening or extension of the device, and the dropping of the side wall 4, the braces 6 are withdrawn from the openings 17 as well as openings 19 of section 2 so 55 as to enable the slide bars 12 to be moved

over the hinged connections 8. Each brace is then inserted into the opening 19 and its registering opening 18 of the slide bar whereupon said brace, which is provided with a locking notch 20 is engaged with the edges of the two openings mentioned. In this manner, it will be obvious that not only the side wall 4 is braced and supported in its vertical position, but the slide 12 is also held from displacement over the pivot or maintained in engagement with its interlocking lug 15 seated in the recess 12'. These braces also serve to hold the slide members 12 when the device is in folded position, as shown in Fig. 5 against likelihood of dropping across the hinge connection or causing binding action by tending to move in this manner, since they extend through the openings 17 of the respective slides in this position. The corresponding braces 5 of the movable side walls 3 are adapted in a like manner to interlock with the angle irons of the section 1 when the device is extended by passing through the openings 22 and the openings 23 of the extension slides 7. These slides 7 are also provided with openings 24 intermediate their lengths through which the braces 5 pass when the sections are closed and said openings come into registry with the openings 22 of the section 1, it being understood that the braces 5 in collapsing action are withdrawn from the interlocking connection shown in Fig. 4 to enable the extension slides 7 to move into the section 1 whereupon they are inserted into the interlocking position best disclosed by Fig. 5.

The use of the invention will be apparent from the foregoing description and a device of this character obviously possesses numerous advantages where it is desired to provide a receptacle for holding a bed outfit in compact form, as for instance for camping purposes. In the closed position of Fig. 3 the bed and other articles may be housed and when it is desired to construct the bed, 105 the sections 1 and 2 are unlocked (any desirable lock being provided to hold them in closed position, though not shown in the drawings) and section 2 moved on its pivot until it assumed the position shown in Fig. 2. This section is then pulled outwardly after the side walls 3 and 4 have been dropped so as to withdraw the braces 5 and 6 and when in full extended position the slide bars 12 are moved over the pivotal 110 connections 8, the braces 5 and 6 are then reintroduced into their proper registered openings and interlocked therein so as to support the walls 3 and 4 as well as lock the bed extended in the manner hereinbefore 115 described. It is only necessary then to arrange the bed clothing on the spring 16. The sections 1 and 2 very adequately form wind shields at the foot and head of the bed which is also advantageous in articles of this character.

acter. By the peculiar arrangement obviously a good sized bed may be formed yet the receptacle which comprises its housing elements may be of a minimum size or compact form.

5 Having thus described my invention, what I claim as new is:

1. In a combined trunk and bed of the class described, a pair of complemental sections coöperating to form a receptacle, slide members connecting said sections together and permitting extension of the sections, one of said sections having pivotal connection with the slide members permitting movement of said section into alined position corresponding with the other section whereby to form a bed.

10 2. In a combined trunk and bed of the class described, a pair of complemental sections coöperating to form a receptacle, slide members connecting said sections together and permitting extension of the sections, one of said sections having pivotal connection with the slide members whereby to permit closing of the sections in receptacle form and relative movement of the pivoted section when extended to form a bed, and means for guiding the slide members in their extension movement.

15 3. In a combined trunk and bed of the class described, a pair of complemental sections coöperating to form a receptacle, slide members connecting said sections together and permitting extension of the sections, one of said sections having pivotal connection with the slide members permitting movement of said section into alined position corresponding with the other section whereby to form a bed, and means coöperating with the pivotal connection when the sections are extended to render said pivot rigid.

20 4. In a combined trunk and bed of the class described, a pair of complemental sections coöperating to form a receptacle, slide members connecting said sections together and permitting extension of the sections, one of said sections having pivotal connection with the slide members permitting movement of said section into alined position corresponding with the other section whereby to form a bed, means coöperating with the pivotal connection when the sections are extended to render said pivot rigid, and means coacting with the last-mentioned

25 55 means and the pivoted section to lock the parts in extended position.

5. In a combined trunk and bed of the class described, a pair of complemental sections coöperating to form a receptacle, slide members connecting said sections together and permitting extension of the sections, one of said sections having pivotal connection with the slide members permitting movement of said section into alined position corresponding with the other section whereby

30 to form a bed, means coöperating with the pivotal connection when the sections are extended to render said pivot rigid, and means coacting with the last-mentioned means and the pivoted section to lock the parts in extended position, said means constituting a supporting brace.

6. In a combined trunk and bed of the class described, a pair of complemental sections pivotally connected for closing into receptacle form, extension means intermediate the sections permitting relative movement thereof to form a bed, and slide members movable into coöperation with the pivotal connection for holding the pivot rigid when the sections are extended.

7. In a combined trunk and bed of the class described, a pair of complemental sections pivotally connected for closing into receptacle form, extension means intermediate the sections permitting relative movement thereof to form a bed, slide members movable into coöperation with the pivotal connection for holding the pivot rigid when the sections are extended, one of the sections having a wall member movable to form a support for the bed, and brace means for said wall member.

8. In a combined trunk and bed of the class described, a pair of complemental sections pivotally connected for closing into receptacle form, extension means intermediate the sections permitting relative movement thereof to form a bed, slide members movable into coöperation with the pivotal connection for holding the pivot rigid when the sections are extended, one of the sections having a wall member movable to form a support for the bed, and brace means for said wall member, said brace means interlocking with a slide member when the latter coacts with a pivot holding the slide member from displacement and bracing the wall member.

9. In a combined trunk and bed of the class described, a pair of pivoted sections adapted to be closed to form a receptacle and when extended to form a bed, each section comprising a movable side adapted to form a support for the sections when in extended position, and braces carried by the movable sides, said braces being withdrawable from the receptacle upon movement of the sides and constituting automatically engaging locking means for holding the sections extended.

10. In a combined trunk and bed of the class described, a pair of complemental sections adapted to form a receptacle when closed and when extended to form a bed, each section having a movable side constituting a support for holding the bed in elevated position, extension slide members intermediate the sections and having interlocking connection therewith, means limiting extension
